BERTH

James K. Tully, Evanston, Leif Andersen, Chicago, and Basil E. Jones, Flossmoor, Ill., assignors to The Pullman Company, Chicago, Ill., a corporation of Illinois

Application March 27, 1941, Serial No. 385,474

6 Claims. (Cl. 155—6)

Two of the principal aims of the railway passenger car industry today are to increase travel comfort and to decrease travel costs to the public. The first of these objectives is always in the minds of car designers as they work out new arrangements, and, in order to insure comfort, each passenger must have adequate room in which to move around without disturbing his neighbor. Comfortable, roomy seats for daytime travel are essential, with ample arm, leg, and head room to permit the traveler to have a certain amount of freedom to move about without annoying his neighbor. At night time, the maximum degree of comfort is insured only if each seat occupant has a roomy, comfortable bed in which to sleep. These requirements for comfort must be satisfied without in any way increasing the size of the car, since the overall dimensions are limited by clearance requirements.

The cost to the public of a particular railway passenger car accommodation depends upon what portion of the total revenue expected from the particular car that accommodation must earn. In order to meet the overhead chargeable against each car and to realize a reasonable profit on the investment, each car must be capable of earning a certain specified sum. To reduce the per capita charge made to the occupants of the car, it is necessary to increase the number of passengers who will share in paying this specified sum.

We find, then, that the two aims previously stated are somewhat contradictory in the results which they produce. The first aim would seem to require more room to be given to each individual passenger in order to insure his comfort, whereas the second aim requires the space available to each occupant to be reduced in order to increase the capacity of the car. These two objectives, however, must be worked out together with the thought in mind always of guaranteeing a certain standard degree of comfort to the traveling public.

Recently, a new type of passenger car accommodation known as the coach sleeper was introduced to the traveling public. The capacity of this car is very nearly that of some of the standard day coaches in service today, and yet each occupant is provided with almost all of the conveniences of an up-to-date Pullman sleeping car. Roomy, comfortable beds are arranged in tiers of three with the lower berth convertible into a plurality of seats for daytime use and the intermediate berth adapted to pivot upwardly into the

upper region of the car directly below the upper berth, so as to give ample head room above the sofa. The intermediate berth is supported in a pan which extends substantially in a vertical position when the berth is in condition for use as a bed. This pan serves the dual function of supporting the berth and forming one of the walls closing the intermediate berth.

The present invention relates particularly to the intermediate berth. As shown, it forms one berth in a tier of three, and is foldable into the upper region of the car to be entirely out of the way during the daytime, so as not to obstruct the portion of the room normally used. This berth, however, has many uses other than in conjunction with berths at different levels, as it has definite utility by itself. For example, it can be used in a room in which movable chairs or other types of seats are employed for daytime travel, and at this time the berth will be in its raised position in the upper region of the room. At night time the berth is lowered into position for use as a bed. It is strong and easy to manipulate. It is out of the way during the daytime and is a comfortable, readily accessible bed at night. The berth can be folded to its inoperative position in its fully made up condition.

The above constitutes some of the principal objects and advantages of the present invention, others of which will become apparent from the following description and drawings, in which

Fig. 1 is a longitudinal sectional view through a car showing a three occupant room made up for day use and a six occupant room made up for night use;

Fig. 2 is an enlarged vertical sectional view taken crosswise of the upper and intermediate berths showing in solid lines the relative positions of the upper and intermediate berths when in their daytime position and indicating in broken lines the intermediate berth in position for night use with a counter-balancing mechanism associated with the intermediate berth;

Fig. 3 is an enlarged detail view of a portion of the upper and intermediate berths;

Fig. 4 is a sectional view taken on the line 4—4 of Fig. 2 showing the upper and intermediate berth arrangements when they are in position for night use, portions of the figure being broken away;

Fig. 5 is an enlarged detail view of a portion of the upper and intermediate berths when in their daytime position taken on the line 5—5 of Fig. 2;

Fig. 6 is an enlarged detail view of the wall

bracket which supports the intermediate berth in its day position, taken on the line 6—6 of Fig. 2; and

Fig. 7 is a fragmentary perspective view of a car showing the intermediate berth in its inoperative position in the upper region of the room.

This application is a continuation in part of the copending application of Peter Parke, James K. Tully, Leif Andersen, and Basil E. Jones, Ser. No. 348,670, filed July 31, 1940, which became Patent No. 2,323,620 on July 6, 1943.

Specific embodiments of the present invention are selected for the purpose of disclosure in accordance with the provisions of Section 4888 of the Revised Statutes. Many modifications may be made without departing from the scope of the invention.

For the purposes of illustration, the berths forming the subject matter of the invention are shown in rooms 56 of a railway car (see Figs. 1 and 7). The rooms are disposed along one car side having windows 82 and are separated from each other by transverse partitions 84. The fourth wall of each room is formed by an aisle partition 85, which separates the rooms from an aisle 55 extending lengthwise of the car.

Each room is provided with berths arranged in a tier of three with the lower one convertible into a sofa 87, the upper berth 88 assuming a stationary position in the upper region of the room, and the intermediate berth 89 foldable to a position adjacent to the underneath face of the upper berth 88, as shown in Fig. 1. The intermediate berth is adapted to assume a horizontal position for use, and is provided with a pan 263 (Fig. 1), which may be let down over the opening in the transverse partition.

Of course the room may be further provided with equipment to make the room furnishings complete both for day and night use.

The berths are so arranged that they may be fully made up with the proper bedding. Thus, the porter is not required to make up beds at night when he is converting the car into a sleeper for night use. Much time is thereby saved, and the porter merely is required to assemble the berths for night use.

Intermediate berth structure

The intermediate berth structure or assembly 89 (Fig. 4) includes an intermediate berth pan 263 comprising a bottom 264 having upright side or end walls 265 and front and rear upright walls 266 and 266', respectively (Fig. 2).

Referring to Fig. 4, the berth pan is pivoted to the car side wall and the aisle partition about a pivot member 267 on each side of the pan. One of the pivot members 267 is supported on the car side wall 53 and the other is supported on the aisle partition 85. When in its closed daytime position, the berth pan 263 is held in a substantially horizontal position directly below the upper berth, as shown in Fig. 2, by a bracket member 268 disposed at each end of the berth pan, one bracket being recessed in the car side wall 53 and the other in the aisle partition 85. (See Figs. 2 and 4.)

Referring particularly to Fig. 6, each bracket 268 comprises a bracket casing 269 which fits into a well in the wall and has a peripheral flange 270, through which the casing is secured to the wall. Extending outwardly from the inner face of the casing 269 is a lug 271 having an opening 272 adjacent to its outer edge. The

bracket 268 is pivoted to the casing 269 at 273 about a vertical axis, so that this bracket may be swung about the pivot point into the closed position in which the outer surface 274 lies flush with the outer surface of the peripheral flange 270. An arm 275 is pivoted to the bracket 268 on the inside thereof about a vertical axis 276. The arm 275 extends inwardly into the casing 269 and through the opening 272 in lug 271. A coil spring 277 surrounds the arm 275 and is held between the lug 271 and a shoulder 278 on the arm 275.

When the bracket 268 is in its open position, as shown in Fig. 6, the spring 277 is compressed between the shoulder 278 and the lug 271 to urge the bracket in its open position. When closing the bracket 268, force is applied to overcome the force of spring 277 and move the bracket in a counter-clockwise direction about pivot point 273. During the closing of this bracket, pivot point 276 rotates about pivot point 273 until it reaches dead center in line with the pivot point 273 and the opening 272 in lug 271, at which time the effect of the spring 277 in maintaining the bracket 268 in open position is overcome. Upon further closing of the bracket 268, pivot point 276 moves to a point inwardly of dead center position, so as to apply counter-clockwise force on the bracket 268 to urge the bracket in the closed position. Thus, the effect of the spring when the bracket 268 closely approaches the closed position is to snap the bracket to and hold it in the closed position.

An intermediate berth 279 closes into and is held by the intermediate berth pan 263, and comprises a frame, (Figs. 2-4, inclusive), made up of angle members 280 secured together in the form of a rectangle with a sheet of canvas 281 closing the bottom of the rectangular frame and secured to the angle members 280. The intermediate berth frame is pivoted to the side walls 285 of the intermediate berth pan 263 at 282 and 283 adjacent to the front wall 266 of the berth pan. Brackets 284 and 285 are secured to the opposite side walls 285 of the berth pan, and each has a centrally inwardly offset portion 286 to which the intermediate berth is journaled. As best shown in Fig. 2, a chain 287 at each end of the intermediate berth has one end secured to the outer end of the intermediate berth pan and has its other end secured to the outer end of the stationary upper berth 88 to suspend the outer edge of the intermediate berth from the upper berth. The berth includes a mattress 288 which is held in the intermediate berth frame.

In Fig. 2, the intermediate berth is shown in its closed position housed in the intermediate berth pan 263 held against the underneath face of the upper berth by brackets 268. A plate 289 is fastened to the underneath face of the bottom 264 of the intermediate berth pan adjacent to the bracket 268 at each end of the berth. To lower the intermediate berth, an upward force is applied under the front edge of the berth pan, and the brackets 268 on both sides of the berth pan are snapped to their closed position. The berth pan is then allowed to rotate downwardly in a counterclockwise direction about its pivot points 267 (Fig. 4) until it assumes the vertical position shown in dotted lines at 290 in Fig. 2. Latches 291 engaging catches 292 on the outer edge of the berth pan hold the intermediate berth pan in this vertical position. The intermediate berth is held in the intermediate berth pan by a latch 293 (Fig. 3) fitting into a slot 294 in

each side of the intermediate berth pan. When lowering the intermediate berth from the pan, it is first unlatched; then rotated about its pivot points 282 and 283 (Fig. 4) until it assumes the horizontal position shown in dotted lines 293 in Fig. 2, the chains 287 supporting the outer edge of the berth.

The intermediate berth pan with the weight of the intermediate berth is counter-balanced at each end by a coil spring 294 (Fig. 2), which extends at right angles to the berth and is fastened at one end to a bracket 295, secured to a wall of the room. A chain 296 is attached to the opposite end 297 of spring 294 and passes over a sprocket wheel 298 journaled to the room wall, and then downwardly to a chain clevis 299 pivoted to one of the side walls 265 of the intermediate berth pan at 300. A counter-balancing spring 294 is provided at each end of the intermediate berth pan, so that two of such springs serve to counter-balance the weight of the intermediate berth.

A housing 301 (Figs. 2 and 5) encloses the counter-balancing springs for intermediate berths on opposite sides of the room (in the case of the six-occupant room), in which case spring 294 (Fig. 2) serves to counter-balance half of the weight of one of the intermediate berths, and spring 294 counter-balances half of the weight of the intermediate berth on the other side of the room. The spring housing 301 is secured to the car wall by screws 302. In this manner, the bulk of the counter-balancing equipment is completely enclosed.

The springs 294 are so arranged that the weight of the intermediate berth overcomes the spring action when the berth assumes a position midway between the closed and open position, so that when lowering the intermediate berth its weight permits it to drop to a position substantially at an angle of 45 degrees with respect to the horizontal, and force is required to place the berth in the vertical position with the pan 263 in the position shown at 290 against the room partition 84.

Berth operation

The operation of the berths is as follows:

Assuming that the berths are in their position for daytime use, as shown at the left side of Fig. 1, and one or more seats are in their semi-reclining position, the first operation which the porter performs to convert the equipment into berths for night use is to place the adjustable seats in their normal upright position shown in Fig. 1. A headboard is first inserted in place at the end of the sofa in the aisle partition to close this space. The sofa back is then rotated in a counter-clockwise direction in a well known manner about its pivot until it comes to rest in a horizontal position (Fig. 1). Next the intermediate berth pan 263 (Fig. 2) is unlatched by rotating the brackets 268 into their wall recesses. The intermediate berth pan is then lowered to the vertical position shown in dotted lines 290 in Fig. 2 and latched in place. The intermediate berth 279 is then unlatched at 259 and rotated down to the horizontal position shown in dotted lines 293. Inasmuch as the upper berth is stationary, the three berths are now in position for use.

We claim:

1. A berth assembly comprising a berth pan having a bottom and front and side walls, pivot means adjacent to one edge of the pan about

which the pan may be rotated from a vertical position to an out-of-the-way horizontal position, a berth including a mattress, the berth with its mattress being foldable into the pan with the top surface of the mattress disposed within the pan, and means pivotally mounting the berth in the pan so that the berth may be pivoted out of the pan when the latter is in its vertical position to a position substantially at ninety degrees to the pan.

2. In a room, a berth assembly foldable into a horizontal position in the upper region of the room and comprising a pan having a bottom, front, rear and end walls, means for supporting the pan including horizontal pivot means adjacent to the rear wall about which pivot means the pan may be pivoted so that the front edge of the pan may be swung downwardly until the pan assumes substantially a vertical position suspended from the pivot means, and a berth including a frame and a mattress projecting above the frame, the berth being pivotally mounted in the pan and movable about said last mentioned pivot mounting from an inoperative position in the pan to a horizontal operative position substantially at right angles to the pan bottom, the front wall of the pan having a height no less than the total thickness of the berth, the rear wall having a height no less than the height of the projecting portion of the mattress, and the end walls of the pan tapering in height from the front to the rear walls.

3. In a room, a berth assembly foldable into a retracted horizontal position in the upper region of the room and movable into an extended horizontal position at a lower level in the room, said structure comprising a pan having a bottom and a front wall and two side walls rigid on the bottom, means for supporting the pan including horizontal pivot means adjacent to one edge of the pan about which the pan may be swung downwardly about the pivot axis until it assumes substantially a vertical position suspended from the pivot means, and a berth pivotally mounted in the pan and movable about said pivot mounting to said horizontal extended operative position from an inoperative initial position retracted in the pan with the berth enclosed by the bottom and walls of the pan.

4. The combination of a berth pan having a bottom and side and front walls, means for supporting the pan including means adjacent to one edge of the pan for mounting the pan in pivotal relation to a fixed support so that the pan can be rotated substantially from a horizontal to a vertical position, means for supporting the pan in a horizontal position, means for locking the pan in its vertical position, a berth including a mattress housed in closed position in the pan with the top surface of the mattress disposed within the pan, means in the pan adjacent to the edge opposite the first mentioned edge for pivotally mounting the berth in the pan, the berth being pivotally movable out of the pan to assume a horizontal open position when the pan is substantially vertical, and means for supporting the berth in said last named horizontal position.

5. In a room, a berth assembly foldable into a substantially horizontal position in the upper region of the room and comprising a pan having a bottom, and front and two side walls permanently connected to the bottom, means for supporting the pan in the upper region of the room including horizontal pivot means adjacent to one edge of the pan about which the pan may be

swung downwardly until the pan assumes substantially a vertical position suspended from the pivot means, a berth including a mattress in the pan, and means connecting the berth to the pan including horizontal pivot means adjacent to one edge of the berth and to the lower edge of the pan when the latter is lowered, about which pivot means the berth may pivot from a position inside the pan to a horizontal position projecting substantially at right angles from the pan, the front and side walls of the pan being of sufficient height above the pan bottom to retain bed clothing within the limits of the pan.

6. In a room, a berth assembly foldable into a substantially horizontal position in the upper region of the room and comprising a pan having a bottom and a substantially right angularly extending front wall permanently connected to the bottom, means for supporting the pan in the upper region of the room including horizontal pivot means cooperating with points on the pan remote

from said front wall about which pivot means the pan may be swung downwardly until it hangs substantially vertically from the pivot means, a berth including a mattress in the pan, and means connecting the berth to the pan including horizontal pivot means adjacent to one edge of the berth and to the front wall of the pan, about which pivot means the berth may pivot from a closed position substantially parallel to the pan bottom to a horizontal open position projecting substantially at right angles from the pan, the front wall of the pan being of sufficient height above the pan bottom to retain bed clothing on the berth when the berth is in closed position and the pan hangs vertically and to bridge the space between the pan bottom and the adjacent side edge of the berth when the berth is in open position.
